(57) **CLAIM**

The ornamental design for a visor extender, as shown and described.

DESCRIPTION

FIG. 1 is a front elevational view showing my new design of the claimed invention positioned at a left side of an existing vehicle sun visor;

FIG. 2 is a front elevational view showing the claimed invention positioned at a right side of the existing vehicle sun visor;

FIG. 3 is a left side elevational view thereof;

FIG. 4 is a rear elevational thereof;

FIG. 5 is a right side elevational view thereof;

FIG. 6 is a top plan view thereof; and,

FIG. 7 is a bottom plan view thereof.

In the drawings the broken lines show a vehicle visor and form no part of the claimed design.
